UNITED STATES PATENT OFFICE.

THOMAS HACKERSON, OF NEWARK, ILLINOIS.

TENT.

1,130,728.

Specification of Letters Patent.

Patented Mar. 9, 1915.

Application filed July 20, 1914. Serial No. 851,949.

To all whom it may concern:

Be it known that I, THOMAS HACKERSON, a citizen of the United States, residing at Newark, in the county of Kendall and State of Illinois, have invented certain new and useful Improvements in Tents, of which the following is a specification.

My invention relates in general to tents and more particularly to an improved collapsible tent which will be water and insect-proof.

Considerable annoyance is experienced by the users of tents on account of the difficulty of preventing the ingress of insects and rain and at the same time rendering the tents convenient of access to the occupants. It is usual to provide one end of a tent with folding flaps to permit the occupants to pass in and out, but said flaps cannot be closed so tightly as to render the tents water and insect-proof, and are moreover not readily closed.

The primary object of my invention is to provide a tent which may be readily closed so as to effectively keep out rain and insects, and which at the same time will afford convenient entrance and exit for the occupants.

A further object of my invention is to provide a collapsible tent which may be folded into a comparatively small package when not in use, and which may be readily set up for use.

A still further object of my invention is to provide a tent which will be simple in construction, inexpensive in manufacture, and efficient in use.

My invention will be more fully disclosed hereinafter with reference to the accompanying drawings, in which—

Figure 1 is a perspective view; Fig. 2 an enlarged view of a portion of the ridge pole and front supporting posts, portions being broken away; Fig. 3 an elevational view looking from the right in Fig. 2; Fig. 4 a detail elevational view of the rear post and adjacent portion of the ridge pole, portions being broken away; Fig. 5 a detail plan view of one end of one of the sections of the ridge pole; Fig. 6 an enlarged cross sectional view on line 6, 6, Fig. 3; Fig. 7 an elevational view of the ridge pole and rear and front supporting posts; Fig. 8 a front elevational view showing the door in open position; Fig. 9 a side elevational view of one of the struts of the ridge pole; Fig. 10 an elevational view looking from

the right in Fig. 9; and Fig. 11 a detail view showing the wire fabrics for closing the window openings.

Similar reference characters are used to designate similar parts in the several figures of the drawings.

Reference letter A indicates the tent covering, which may be of any suitable material, and of any desired size and shape.

a designates the usual guy-rope for retaining the tent covering in distended position.

B indicates the front wall of the tent which is provided with one or more window openings b.

C designates the ridge pole of the tent which is formed of detachable aligned tubular sections C', C² and C³. The joints between the sections of the ridge pole are strengthened by means of coupling tubes c, which are inserted within and extend across the ends of the adjoining sections, as shown in Fig. 2. The ends of adjoining sections of the ridge pole are provided with complementary lugs c' and notches c² which interlock to prevent the sections of the ridge pole from relatively rotating.

D designates an elbow which connects the rear end of the ridge pole C with the upper end of a post E, the latter being preferably formed in detachable sections, the lower one of which is formed with a spike e' to be inserted in the ground. E' designates a base plate surrounding the lower end of the post E immediately above the spike e' for resting upon the ground and affording a more secure support for the post.

F designates a coupling member comprising a horizontal tubular portion f which aligns with, and is connected to, the end of the adjacent section C³ of the ridge pole. The coupling member F also comprises two vertical tubular sockets F', F² within which are pivotally supported the upper ends of two oscillatory front posts G' and G². The lower ends of the front posts G' and G² are provided with vertical cylindrical portions, which are received in tubular sockets H' and H² formed in a base H, the latter being provided with a spike h' to enter the ground. Each of the front posts G' and G² is preferably of a cross section substantially as shown in Fig. 6 so as to provide longitudinal channels i' and i² in the outer surfaces thereof. Each of the front posts is preferably formed in two or more sections,

the adjacent ends of which overlap and are rigidly secured together by suitable fastening devices, such for instance as bolts and winged nuts g , as shown in Fig. 6.

5 L' and L^2 designate wire ropes connected at their ends to the respective front posts G' and G^2 adjacent their upper ends. The lower ends of the ropes L' and L^2 are connected with coiled springs l' , l^2 , which in turn are connected to the respective posts G' and G^2 adjacent their lower ends. The ropes L' and L^2 are yieldingly retained in the channels i' , i^2 in the front posts by means of the coiled springs l' and l^2 . The front wall B of the 10 tent is formed in two sections between which are located the pair of oscillatory posts G' and G^2 , the sections of the front wall of the tent adjacent the posts being secured to them by means of the ropes L' and L^2 .

15 20 In order to retain the pair of posts G' , G^2 in the closed position shown in Fig. 1, any suitable latch may be provided, as shown in Fig. 3, comprising a pivoted member K' on one of the posts and keeper K^2 engaged thereby on the other post.

25 In order that the ridge pole may possess the requisite strength, a tension rope M is preferably provided, one end of which is provided with a hook m' , which engages an 30 eye-bracket M' fixed to the under side of the elbow D , while the other end of the rope M is connected to a bracket M^2 secured to the under side of the tubular portion f of the front coupling F by any suitable adjusting 35 means, such for instance as a bolt and winged nut m^2 . Struts N are interposed between the ridge pole C and the tension rope M , such struts being preferably constructed as shown in Figs. 9 and 10, in which n^2 designates a 40 ring at the upper end of each strut which surrounds the ridge pole, and n' a notch at the lower end of each strut in which is seated the tension rope M . The ring n^2 may be tightly clamped about the ridge pole by 45 means of a bolt and nut n .

50 The window openings b in the front wall of the tent are preferably closed by cord fabric O of a size to prevent ingress of insects. The cord fabric O is preferably reinforced by a fabric o made of heavier cords. The window openings are also preferably provided with curtains which may be secured in rolled position at the tops of the openings, as shown in Fig. 8, and there retained 55 by suitable straps p .

60 The tent may be readily set up by coupling together the section of the ridge pole C , and by then imparting to the rope M sufficient tension to retain the sections of the ridge pole in coupled relation, and to impart to the ridge pole the requisite strength to support the weight of the tent covering. The rear post E is then connected with the rear end of the ridge pole, and the pair of 65 front posts G' and G^2 pivotally connected

with the front end of the ridge pole through the medium of the coupling member F . The lower ends of the pair of front posts are then pivotally supported upon the ground by means of the base member H . The ropes L' and L^2 are extended through folds formed along the edges of the tent material at each side of the front opening, and are then connected with the pair of front posts so as to securely connect the adjacent edges of the two sections of the front wall of the tent securely thereto.

70 75 In order that the tent may open so as to permit the occupants to pass in or out, the front posts are swung away from each other, as indicated in Fig. 8. When it is desired to close the tent opening the front posts are swung toward each other into contact and are retained in such position by means of the latch.

80 85 Inasmuch as the front posts are offset intermediate of their ends, it is obvious that when they are swung apart an opening is formed to permit access to the tent, while when the front posts are swung together, 90 said opening will be tightly closed so as to effectively prevent ingress of insects or rain.

95 It is obvious that the tent may be compactly folded when not in use, inasmuch as the ridge pole, as well as the rear and front posts, may be taken apart and the sections forming them disconnected.

100 105 From the foregoing description it will be observed that I have invented an improved tent which will permit the occupants to have free access thereto, but may be readily closed so tightly as to render the same rain and insect-proof.

I claim:

110 115 1. The combination with a tent, of a pair of oscillatory posts correspondingly offset between their ends, means for pivotally supporting the upper and lower ends of said posts adjacent each other, and means for securing to said posts the tent covering at each side of an opening therethrough.

120 125 2. The combination with a tent, of a pair of oscillatory posts correspondingly offset between their ends, means for pivotally supporting the upper and lower ends of said posts adjacent each other, means for securing to said posts the tent covering at each side of an opening therethrough, and means for detachably fastening said posts together intermediate of their ends.

130 135 3. The combination with a tent, of an oscillatory post offset between its ends, means for pivotally supporting the upper and lower ends of said post within an opening in the tent covering, means for securing to said post the tent covering at one side of the opening therethrough, and means for retaining said post in position to close the opening.

4. The combination with a tent, of an oscillatory post offset between its ends and

having a longitudinal channel in the outer surface thereof, a rope secured at its ends adjacent the top and bottom of said post and lying within the channel therein, a coiled spring interposed between one end of said rope and its connection with the adjacent end of the post, means for securing to said rope the tent covering at one side of the opening therethrough, and means for retaining said post in position to close the tent opening.

5. In a collapsible tent, the combination with a ridge pole comprising alining separable sections, of a post comprising detachable sections movably connected with one end of said ridge pole, a pair of oscillatory posts correspondingly offset between their upper and lower ends and formed with detachable sections, means for detachably pivotally con-

necting the upper ends of said pair of posts 20 with the other end of said ridge pole, and means for pivotally supporting the lower end of said pair of posts adjacent each other upon the ground.

6. In a collapsible tent, a ridge pole comprising alined tubular sections, the ends of adjacent sections having engaged lugs and notches, a flexible tension member connected at its ends to the ends of the ridge pole, and struts interposed between the ridge pole and 30 said tension member.

In testimony whereof, I have subscribed my name.

THOMAS HACKERSON.
